UNITED STATES PATENT OFFICE

152,951

DESIGN FOR A FOOT MASSAGER

Jack Eldredge, Cleveland, Ohio

Application April 14, 1947, Serial No. 138,367

Term of patent 14 years

(Cl. D83—1)

To all whom it may concern:

Be it known that I, Jack Eldredge, a citizen of the United States, residing in the city of Cleveland, county of Cuyahoga, and State of Ohio, have invented a new, original, and ornamental Design for a Foot Massager, of which the following is a specification, reference being had to the accompanying drawing, forming a part thereof.

Figure 1 is a front view of a foot massager embodying my new design;

Figure 2 is a cross sectional view thereof taken along the line and in the direction of the arrows 2—2 of the Figure 1; and

Figure 3 is an end view thereof.

The device is symmetrical and the top, bottom and rear views are the same as the front view.

I claim:

The ornamental design for a foot massager, substantially as shown and described.

JACK ELDREDGE.
